UNITED STATES PATENT OFFICE.

PRIOR M. GUIOU AND JAMES R. GUIOU, OF KANSAS CITY, MISSOURI,
ASSIGNORS OF ONE-THIRD TO THOMAS J. STEPHENS, OF KANSAS
CITY, MISSOURI.

UMBRELLA.

No. 824,178.

Specification of Letters Patent.

Patented June 26, 1906.

Application filed May 27, 1904. Serial No. 210,028.

To all whom it may concern:

Be it known that we, PRIOR M. GUIOU and JAMES R. GUIOU, citizens of the United States, residing at Kansas City, in the county of Jackson and State of Missouri, have invented certain new and useful Improvements in Umbrellas, of which the following is a specification.

Our invention relates to improvements in umbrellas.

The object of our invention is to provide an umbrella that can be folded so as to occupy small space for convenience in packing in a trunk, satchel, or other receptacle.

Our invention consists in the novel features of construction hereinafter fully described and claimed.

In the accompanying drawings, which illustrate our invention, Figure 1 is a view, partly in side elevation and partly in vertical section, of an umbrella constructed in accordance with the principles of our invention, the umbrella being shown opened and the rod extended. Fig. 2 is a top view of the sleeve and runner, the rod being shown in cross-section. Fig. 3 is a cross-section taken on the dotted line *a b* of Fig. 6. Fig. 4 is an elevation view of the central member, detached, of the rod. Fig. 5 is a side elevation view of the center member of the rod and parts of the other two members connected therewith. Fig. 6 is a longitudinal vertical sectional view showing the umbrella closed and the rod extended. Fig. 7 is a longitudinal sectional view of the inner end of a stretcher. Fig. 8 is a longitudinal sectional view of the runner and sleeve. Fig. 9 is a side elevation view of the upper end of the runner. Fig. 10 is a view, partly in elevation and partly in longitudinal section, of part of a rib and part of a stretcher connected thereto. Fig. 11 is a side elevation view of the umbrella shown folded, some of the stretchers and ribs and the cover being removed.

Similar characters of reference denote similar parts.

1 denotes the upper member of the rod, 2 the central member, and 3 the lower member thereof. The ends of the members 1 and 3 adjacent the member 2 are pivoted to the member 2, so as to be swung to the folded position (shown in Fig. 11) or extended, as shown in Fig. 1. On the rod is mounted a slideable locking device 4, preferably in the form of a

sleeve, which encircles the rod and is movable to and from a position covering the hinged ends of the members 1, 2, and 3. The sleeve prevents the members from folding. On the sleeve 4 and the rod is mounted a tubular runner 5, the upper end of which is provided with two resilient arms 6, having inwardly-turned upper ends for engaging the upper end of the sleeve 4 for drawing the sleeve downwardly when the runner is moved downward. In the lower end of the runner is a ring 7, having a longitudinal slot 8 to admit therethrough an abutment, comprising a pin 9 on the member 3. The ring 7 serves to engage and move the sleeve 4 upward when the runner is upwardly moved. The pin or abutment 9 serves to limit the downward movement of the sleeve 4, so that it may remain covering the hinged ends of the rod members when the runner 5 is moved to the position shown in Fig. 6. On the upper end of the member 1 is a notch 10, to which are pivoted the inner ends of the inner sections 11 of the ribs. The ribs comprise the said inner members and the outer members 12, pivoted thereto, as follows: The outer end of each inner section 11 is secured to a U-shaped shoe 13, between the sides of which the inner end of the outer section 12 is pivoted. The shoe 13 on its outer end extends beyond the inner end of the section 12, thus supporting on its upper side the said outer section when said section is extended, as shown in Fig. 10. The ribs are swung on the notch 10 by means of the stretchers, each comprising an inner tubular section 14, the inner end of which is pivoted to the upper end of the runner 6. In 90 the outer end of the section 14 is slideable lengthwise the inner end of the outer section 15, the outer end of which is pivotally connected to the inner rib-section 11. On the inner end of the section 15 is a cylindrical enlargement 16, against the inner end of which bears a coil-spring 17, the tension of which is to normally force the section 15 outwardly. As shown in Fig. 7, the outer end of the inner section 14 of each stretcher is provided with an inner annular flange 18, which prevents the cylindrical portion 16 of the section 15 passing out the section 14.

In the member 3 of the rod is provided an inwardly-movable catch 20, adapted to enter 105 a slot 21 in the runner 5 when the runner is

in the position shown in Fig. 6. A similar catch 22 is provided above the catch 20 for supporting the lower end of the runner 5 when the runner is in the position shown in 5 Fig. 1.

In operating our invention to raise the umbrella the runner 5 is forced upwardly to the position shown in Fig. 1, thus forcing outward the stretchers and forcing outwardly 10 the ribs, thus stretching the cover 23, mounted on said ribs. The adjacent edges of the different sections forming the cover are joined together, so as to form radial pockets 24, in which the rib-sections are mounted. 15 By this construction the cover need be secured to the ribs only near the outer ends of the ribs, as denoted by 25. If it is desired to close the umbrella, but not to fold it, the catch 22 is depressed and the runner 5 drawn to the 20 position shown in Fig. 6. The arms 6, engaging the upper end of the sleeve 4, will draw the sleeve downward until it strikes the pin 9, when the resilient arms 6 will be forced outward, and the runner 5 will be permitted 25 to move downward until the catch 20 enters the slot 21. The runner in moving downward will draw down the stretchers and ribs to the positions shown in Fig. 6. To fold the 30 umbrella, the runner 5 is moved upwardly until its upper end strikes the notch 10. In moving upward with the runner the ring 7 strikes the lower end of the sleeve 4 and carries the sleeve upwardly until the hinged ends of the members 1, 2, and 3 are uncovered, at 35 which time the members 1, 2, and 3 may be swung to the positions shown in Fig. 11. The outer rib-sections 12 may then be swung to the 40 positions shown in Fig. 11, at which time the umbrella will be occupying much less space in length than when in the extended position, and it may then be conveniently packed away in a trunk or small parcel. The compressible springs 17 in the inner stretcher-sections 14 permit the longitudinal movement 45 of the outer stretcher-sections 15 to a position such that the upper end of the runner 5 will move from the position shown in Fig. 1 to a position adjacent the notch 10. The strength of the springs 17 is such that 50 when the runner 5 is moved to the position shown in Fig. 1 the sections 15 of the stretchers will be forced outwardly with sufficient force to tightly stretch the cover 23. In order that the outer sections 12 of the ribs 55 may lie parallel with the inner sections 11 when folded, as shown in Fig. 11, the inner end of each said sections 12 is pivoted a little outside of a straight line forming an extension of the section 11 connected therewith, 60 and to permit the outer section to lie in the same line as the inner section the inner end of section 12 is slightly curved outwardly, as denoted by 26 in Fig. 6.

Our invention may be modified in different 65 ways without departing from its spirit.

Having thus described our invention, what we claim, and desire to secure by Letters Patent, is—

1. In an umbrella, the combination with a rod comprising a plurality of members hinged to each other at adjacent ends so as to be folded, of a locking device slidably mounted on the rod and adapted to be moved thereon so as to embrace the rod at each side of the hinged connection when the rod is extended, and a runner slidably mounted on the rod and encircling and movable longitudinally upon said locking device and provided with means for engaging and sliding said locking device lengthwise on the rod in either direc- 70 75 80

2. In an umbrella, the combination with a rod comprising a plurality of members hinged to each other at adjacent ends so as to be folded, of a sleeve slidably mounted on the 85 rod and movable thereon to and from a position in which it will embrace the rod at each side of the hinged connection when the rod is extended, and a runner slidably mounted on the rod and encircling and movable length- 90 95 wise upon the sleeve and provided with means for engaging and sliding said sleeve lengthwise on the rod in either direction.

3. In an umbrella, the combination with a rod comprising a plurality of members hinged to each other at adjacent ends so as to be folded, of a sleeve slidably lengthwise on the rod and movable to and from a position in which it will embrace the rod at both sides of the hinged connection, means for limiting the 100 downward movement of the sleeve to stop the sleeve in a position covering said hinged ends of said members, and a runner slidably lengthwise on the rod and having a yielding 105 arm for engaging and moving the sleeve in one direction and against said limiting means, and provided with means for engaging and sliding the sleeve lengthwise in the other direction.

4. In an umbrella, the combination with a 110 rod comprising a plurality of members hinged at their adjacent ends, one member being provided with an abutment, of a sleeve slid- 115 able lengthwise on the rod and disposed when moved against said abutment so as to cover said hinged ends, and a tubular runner slid- 120 able lengthwise on said sleeve and on said rod and provided with yielding means for engaging and moving the sleeve to a position covering said hinged ends of said members and having means for moving the sleeve in the opposite direction.

5. In an umbrella, the combination with a rod comprising a plurality of members hinged at their adjacent ends one member having 125 mounted thereon an abutment, of a sleeve slidable lengthwise on the rod and movable against and from said abutment, and when positioned against said abutment covering said hinged ends of said members, and also 130

slidable to a position uncovering said hinged ends, and a tubular runner slidably mounted on said sleeve and said rod, and provided with a resilient releasable device for engaging 5 and sliding the sleeve against said abutment when the runner is properly moved in one direction, the runner being provided with means for engaging and sliding the sleeve in the opposite direction when the runner is so 10 moved.

6. In an umbrella, the combination with a rod comprising a plurality of members hinged together at adjacent ends, of a plurality of foldable ribs hinged to one of said members, 15 a locking device slidable on the rod and movable to and from a position covering said hinged ends of said members, a runner slid- 20 able on said rod and provided with resilient arms for engaging and sliding said locking device lengthwise of the rod in one direction and provided with means for sliding the locking device in the opposite direction, and a plurality of stretchers pivotally connected to 25 said runner and to said ribs.

7. In an umbrella, the combination with a rod comprising a plurality of members hinged together at their adjacent ends, of a plurality of foldable ribs hinged to one of said members, a sleeve slidably mounted on the rod 30 and movable to and from a position covering the hinged ends of the said members, a tubular runner slidable lengthwise on the sleeve and on the rod and provided with yielding arms for sliding the sleeve in one direction, 35 and having means for sliding the sleeve in the opposite direction, and a plurality of stretchers pivotally connected to the runner and to said ribs.

8. In an umbrella, the combination with a 40 rod comprising a plurality of members hinged together at their adjacent ends and having on one member a notch and on one of the other members an abutment, of a plurality of foldable ribs hinged to said notch, a sleeve slid- 45 able on the rod between the notch and the abutment and when moved to a position against the abutment covering said hinged ends of said members, and uncovering said ends when moved against the notch, a tubu- 50 lar runner slidable on the sleeve and rod, and provided with yielding arms for engaging and sliding the sleeve against the abutment and having means for moving the sleeve in the opposite direction, and a plurality of stretch- 55 ers hinged to said runner and to said ribs.

9. In an umbrella, the combination with a rod comprising a plurality of members hinged together at their adjacent ends, of a plurality of foldable ribs pivotally connected to one of 60 said members, a sleeve slidable on said rod to and from a position covering the hinged ends of said members, a tubular runner slidable on the rod and encircling and slidable on the sleeve and provided with yielding means for 65 sliding the sleeve in one direction and having

means for engaging and sliding the sleeve in the opposite direction, a plurality of stretchers comprising each two members longitudinally movable with respect to each other, said stretcher members being pivotally connected respectively to the runner and to said foldable ribs, and a plurality of springs for normally forcing the outer stretcher members outwardly. 70

10. In an umbrella, the combination with a rod comprising a plurality of members hinged together at their adjacent ends, of a locking device for releasably locking said members in the extended position, a runner slidable lengthwise on said members, movable relative to and provided with yielding arms for engaging and moving said locking device to a position in which said members will be held extended, a plurality of foldable ribs connected to and movable relative to one 80 of said members, and a plurality of stretchers connected to the runner and to the foldable ribs. 85

11. In an umbrella, the combination with a rod comprising a plurality of members hinged together at their adjacent ends, of a locking device for releasably locking said members in the extended position, a runner slidable lengthwise on said members, movable relative to and having yielding arms for 90 engaging and moving said locking device to a position in which the locking device will hold said members extended, a plurality of foldable ribs pivoted to one of said members, and a plurality of lengthwise-extensible stretchers, provided with resilient means for normally extending said stretchers, the stretchers being connected respectively to the foldable ribs and the runner. 95

12. In an umbrella, the combination with a rod comprising a plurality of members hinged together at their adjacent ends, of a locking device for releasably locking said members in the extended position, a runner slid- 100 able on said members and controlling said locking device, a plurality of foldable ribs pivoted to one of said members, a plurality of stretchers comprising each two sections, one a tubular section pivoted at its inner end to the runner, the other section being longitudinally movable in the tubular section, and pivoted to an adjacent rib, and a plurality of springs disposed one in each tubular section and normally forcing outwardly the other section. 110

13. In an umbrella, the combination with the rod comprising a plurality of members hinged together at their adjacent ends, of means for releasably locking said members in the extended position, a runner longitudinally slid- 115 able on said members and controlling said locking means, a plurality of ribs each comprising two sections the inner of which is pivoted to the upper staff member, the two sections being hinged together, and a 120

plurality of stretchers comprising each an inner tubular section and an outer section movable lengthwise therein, the inner section being pivoted to the runner, and the outer section being pivoted to the inner section of the adjacent rib, and a plurality of coil-springs mounted one within each inner section of the stretcher and bearing upon and normally forcing the adjacent section of the stretcher lengthwise outwardly.

14. In an umbrella, the combination with a rod, of a runner movable lengthwise thereon, a plurality of ribs comprising each two sections hinged together, the inner section being pivoted to the rod, and a plurality of stretchers each comprising a tubular inner section pivoted to the runner, an outer section pivoted to the inner section of the adjacent rib and slideable in the tubular inner section, and a coil-spring mounted in each tubular stretcher-section and normally forcing the outer stretcher-section outwardly in the tubular inner section.

15. In an umbrella, the combination with a rod comprising a plurality of members hinged at their adjacent ends, one member having mounted thereon an abutment, of a

30 sleeve slideable on the rod to and from said abutment and when positioned against the abutment covering the hinged ends of said members, a tubular runner slideably mounted on the sleeve and on the rod and provided with yielding means for engaging and sliding the sleeve against said abutment when the runner is moved in one direction, the runner having means for engaging and sliding the sleeve in the opposite direction when the runner is so moved, a plurality of foldable ribs pivoted to one of said members of the rod, a plurality of stretchers comprising each two sections, one a tubular section pivoted at its inner end to the runner, the other section being slideable longitudinally in the tubular section and pivoted to an adjacent rib, and a plurality of springs disposed one in each tubular section and normally forcing outwardly 45 the other section.

35 In testimony whereof we affix our signatures in presence of two witnesses.

PRIOR M. GUIOU.
JAMES R. GUIOU.
